WRITING INSTRUMENT OR SIMILAR ARTICLE

Robert John Darst, Fort Madison, Iowa, assignor to W. A. Sheaffer Pen Company, Fort Madison, Iowa, a corporation of Delaware

Filed Oct. 23, 1965, Ser. No. 87,867

Term of patent 14 years

(Cl. D74—17)

FIG. 1 is a side elevational view of a writing instrument showing my new design as it appears when not in use;

FIG. 2 is a side elevational view rotated 90 degrees from FIG. 1 and showing the writing instrument as it appears in position for writing;

FIG. 3 is a top plan view of FIG. 2; and

FIG. 4 is a bottom plan view thereof.

I claim:

The ornamental design for a writing instrument or similar article, as shown and described.
